UNITED STATES PATENT OFFICE.

MALCOLM H. BAKER, OF BRAINTREE, MASSACHUSETTS; MARIE H. BAKER ADMINISTRATRIX OF MALCOLM H. BAKER, DECEASED, ASSIGNOR, BY MESNE ASSIGNMENTS, TO TREMONT PRODUCTS COMPANY, A CORPORATION OF MASSACHUSETTS.

THERMODYNAMICALLY-CONTROLLED KNIFE SWITCH.

1,407,315.

Specification of Letters Patent. Patented Feb. 21, 1922.

Application filed October 8, 1915, Serial No. 54,882. Renewed April 14, 1919. Serial No. 290,084.

To all whom it may concern:

Be it known that I, MALCOLM H. BAKER, a citizen of the United States, and a resident of Braintree, in the county of Norfolk and 5 Commonwealth of Massachusetts, have invented certain new and useful Improvements in Thermodynamically-Controlled Knife Switches, of which the following is a specification.

10 My invention relates to switches for electric circuits formed with pivoted, or swinging, blades, of the type usually known as "knife" switches.

The object of my invention is to provide, 15 in combination with such a switch, means, under the control of the operator, whereby the said switch may be closed for a continuous period of time, as required for normal operation of the controlled circuit, and 20 whereby, when it is desired to open the switch, an automatically performed opening movement may be had, operative a predetermined time after the actuation of the controlling means of the switch; the preferred 25 arrangement being one whereby the same controlling member, actuated manually or otherwise, which is used to close the switch is also employed to put into operation the delayed automatic opening means.

30 In other applications filed by me I have illustrated and broadly claimed such retarded automatic switch opening devices as broadly applicable to various well known types of switches for electric circuits; and 35 specifically as applicable to snap switches, socket switches, and various other forms.

I have illustrated a preferred embodiment of my present invention in the accompanying drawings, in which Fig. 1 is a front 40 elevation of my improved thermo-dynamically controlled knife switch; Fig. 2 is an elevation looking at the right of Fig. 1; Fig. 3 is a horizontal section taken on the plane A—A in Fig. 1; and Fig. 4 is a diagram of electrical connections.

Throughout the several views of the drawings identical parts are designated by like reference numerals. In the drawings, a base 1, of suitable insulating material, is shown 45 carrying contact clips 2, 3, having engagement with blades 6, 6, which are pivoted in posts 4, 5, mounted upon the base 1. An

insulating bar 7 connects the blades 6, 6. A second structure composed of metal bars 8, 8, having a control handle 10 is pivoted 55 at 12 to the base 1. The blades 6, 6, have rigid connection with an extension 13 to which is attached a coiled spring 14 fast at the other end to the bracket 15 on the base 1. Contact clips 16, 17, are arranged on the 60 base 1 to engage the ends of the pieces 8, 8, when this structure is swung downwardly by means of the handle 10. This engagement closes a shunt circuit, across the clips 16, 17, (see Fig. 4). Spring clips 11 serve 65 to hold the structure 8, 8, in the raised position, and a thermostat 18 having a winding 19, of suitable resistance wire, is attached to a block 20 on the base 1.

The upper end 21 of the said thermostat 70 is bent around a rod 22, said rod engaging with a slot in the end 23 of a bell-crank lever pivoted to the bracket 20 on the base 1.

This thermostat is of the common, laminated type, composed of two surface-united 75 strips of differently expansible metals with the strip of more expansible metal on the rearward or inner side next to the insulating base; so that upon suitable rise in temperature, the unequal expansion of the laminae 80 will cause the thermostat to flex or to bow forwardly or away from said base, thus causing movement of its free end 21, of the rod 22, and of the downwardly extending 85 detent lever end 23 in a direction away from the insulating base 1. The other end of the lever 23, shown at 24, engages a projection 25 on the cross piece 7, so as to hold the switch closed.

The operation is as follows,—to close the 90 switch the handle 10 is pushed up which swings the structure 8, 8, against the cross bar 7, thus carrying up the blades 6, 6, into engagement with their clips 2, 3, to complete the electric circuit. At the same time the 95 projection 25 is engaged by the end 24 of the lever 23, the thermostat giving, or springing, slightly to permit such engagement, and the switch thus locked closed against the action of the spring 14.

When it is desired to open the switch, the handle 10 is pulled down, the said handle moving the structure 8, 8, away from contact with the blade structure 6, 6, and the

manual, or other, controlling pull being sufficient to disengage 8, 8, from the clips 11. This action forces the ends of the pieces 8, 8, into the clips 16, 17, thus connecting the 5 winding 19 in shunt to the switch load. The thermostat is now heated, bends, moves the lever 23 as above described, and frees the end 24 thereof from engagement with the projection 25, thus permitting the spring

10 14 to snap the blades 6, 6, out of their clips 2, 3, to open the circuit.

The desired time element, or delay, between the actuation of the handle 10 and the opening of the circuit is obtained 15 through the time required to heat to operation the thermostat 18, and this time element can of course be broadly varied by altering the amount of wire in the winding 19, or the amount of engagement of the lever 20 end 24 with the projection 25.

It will be noted that, since the thermostat circuit is shunted across the load side of the switch, said circuit is dead when the switch is opened.

25 It is of course easily possible to apply my invention to a single pole knife switch in place of the double pole herein illustrated, in which case the thermostat circuit would be energized by being placed in series with 30 the switch circuit, as set forth in my other applications referred to.

As a thermo-dynamic device to secure opening of the switch I have shown a bimetallic thermostat, but any other suitable 35 type of such device may, of course, be employed.

Without, therefore, limiting myself to the precise embodiment herein shown, what I claim as my invention is,—

40 1. In an electric knife switch having a stationary contact terminal and a pivoted, swingable, blade device adapted at one extreme position thereof conductively to engage with said terminal, in combination;—

45 controlling means arranged by insulated engagement with said device to swing the latter into engagement with said terminal contact and against the resistance of resilient means arranged to oppose such engagement; and a

50 thermo-dynamic device and associated mechanism controlled thereby, adapted when thermally energized to cause the separation of said blade device from said terminal; together with an electric heater for said

55 thermo-dynamic device arranged operatively to be governed by said controlling means.

2. In an electric knife switch having a stationary contact terminal and a pivoted, swingable, blade device adapted at one extreme position thereof conductively to engage with said terminal, in combination;—manually operable controlling means arranged by insulated engagement with said device to swing the latter into engagement 60 with said terminal contact and against the

resistance of resilient means arranged to oppose such engagement; and a thermo-dynamic device with associated mechanism controlled thereby, adapted when thermally energized to cause the separation of said blade 70 device from said terminal; together with an electric heater for said thermo-dynamic device arranged operatively to be governed by said controlling means.

3. In an electric knife switch having a stationary contact terminal and a pivoted, swingable, blade device adapted at one extreme position thereof conductively to engage with said terminal, in combination;—controlling means arranged by insulated engagement with said device to swing the latter into engagement with said terminal contact and against the resistance of resilient means arranged to oppose such engagement; a detent normally positioned to prevent separation of 85 said blade device from said terminal; a thermo-dynamic device operatively related to said detent when thermally energized to cause said separation, together with an electric heater for said thermo-dynamic device 90 arranged operatively to be governed by said controlling means.

4. In a knife switch for electric circuits, including a stationary contact member and a swinging contact member adapted conductively to engage therewith, in combination;—manually controllable means adapted to move said swinging member into circuit making engagement with said stationary member; detent means arranged normally operative to 95 maintain such engagement; a thermo-dynamic device adapted, when thermally energized, to render said detent means inoperative; resilient mechanism arranged tending to separate said swinging member from said 100 stationary member; an electric heater for said thermo-dynamic device; a normally open circuit in shunt to the switch governed load and containing said heater; and auxiliary switch means operably related to said 105 manually controllable means and arranged, upon designed movement of the latter, to close said shunt circuit.

5. In a knife switch for electric circuits, including a stationary contact member and a swinging contact member adapted conductively to engage therewith, in combination;—manually controllable means adapted to move said swinging member into circuit making engagement with said stationary member; detent means arranged normally operative to maintain such engagement; a thermo-dynamic device adapted, when thermally energized, to render said detent means 115 inoperative; resilient mechanism arranged tending to separate said swinging member from said stationary member; an electric heater for said thermo-dynamic device; and normally inoperative circuit connections 120 operably related to said manually controlled 125 means.

lable means and adapted upon designed movement of the latter to energize said heater from the switch circuit.

6. In a knife switch for electric circuits including a stationary contact member and a co-operative swinging contact member, manual controlling means adapted to move said swinging member into engagement with said stationary member, thermostatically governed means adapted to maintain such engagement, spring mechanism adapted to separate said swinging member from said stationary member, an electric heater for the thermostat, a normally open shunt circuit 10 across the switch, and including said heater, and means, governed by a reversed movement of said manual controlling means, adapted to close said shunt circuit.

7. In a knife switch for electric circuits including a stationary contact member and a co-operative swinging contact member, in combination, manual controlling means to move the latter member into engagement with the former member, detent means adapted to retain such engagement, spring mechanism tending to separate said latter member from said former member, a thermostat adapted, when energized, releasingly to move said retaining means, an electric heater for 25 said thermostat, an electric circuit including said heater, and means, controlled by a reverse movement of said manual controlling means from their switch closing position, adapted operatively to relate said last mentioned circuit to the switch circuit.

8. In an automatically-delayed-opening electric knife switch, in combination;—a conductive blade structure pivoted for swinging movement and arranged normally to be 40 automatically locked in circuit-making position at one extreme of its travel, a controlling frame for said structure, also pivoted for swinging movement and arranged by insulated positive engagement with said 45 structure to move the latter into its said circuit-making position, together with automatic instrumentalities arranged operatively on withdrawal of said frame from said structure, to cause delayed circuit-breaking 50 movement of said structure.

9. In a knife switch for electric circuits, in combination; a stationary contact clip; a pivoted blade member adapted conductively to engage with said clip; an auxiliary, pivoted, and manually controllable frame, adapted by insulated engagement with said blade member, to move the latter into circuit-making engagement with said clip, a thermostatically controlled detent arranged normally to retain said blade member in said circuit-making engagement with said clip; auxiliary contacts positioned to be connected electrically by said auxiliary frame when the latter is withdrawn from 65 engagement with said member; an electric

heater for the thermostat; and a circuit, in shunt to the switch governed load, and including said heater and said auxiliary contacts in series therewith; together with spring mechanism adapted to separate said 70 blade member from its associated contact clip, whereby, when said heater is electrically energized by withdrawal of said frame from said member, the said mechanism is automatically rendered operative to open 75 the switch after a predetermined time.

10. An electric knife switch structure including electrically energized means for the automatic control thereof and embodying in combination with a swinging conductive 80 blade and stationary circuit terminals positioned to be contacted thereby in the circuit-making position thereof; an auxiliary, separately pivoted, actuating frame for said blade adapted by positive and insulated engagement in one direction therewith to swing said blade into its circuit-making position; a resilient detent device positioned yieldingly to retain said frame and said blade in said circuit-making position of the 90 latter; and auxiliary stationary circuit terminals operatively related to said means and positioned to be conductively connected by engagement of said frame therewith upon withdrawal of the latter from engagement 95 with said blade and whereby said means are operatively energized.

11. An electric knife switch structure including electrically energized means for the automatic control thereof and embodying in 100 combination with a swinging conductive blade and stationary circuit terminals positioned to be contacted thereby in the circuit-making position thereof; an auxiliary, separately pivoted actuating frame for said 105 blade comprising two side bars having conductive extensions on one side of the pivot and adapted by positive and insulated engagement with said blade on the opposite side of said pivot and by means of an insulated handle secured to said frame, to swing said blade into its circuit-making position; a resilient detent device positioned yieldingly to retain said frame and said blade in said circuit-making position of the 110 latter; and auxiliary stationary circuit terminals operatively related to said means and positioned to be conductively connected by engagement of said frame therewith upon withdrawal of the latter from engagement 115 with said blade and whereby said means are operatively energized.

12. An electric knife switch structure including electrically energized means for the automatic control thereof and embodying in 120 combination with a swinging conductive blade and stationary circuit terminals positioned to be contacted thereby in the circuit-making position thereof; an auxiliary, separately pivoted actuating frame for said 125 blade

blade comprising two side bars having conductive extensions on one side of the pivot and adapted by positive and insulated engagement with said blade on the opposite side of said pivot and by means of an insulated handle secured to said frame, to swing said blade into its circuit-making position; a resilient detent device positioned yieldingly to retain said frame and said 10 blade in said circuit-making position of the latter; and two auxiliary contact clips operatively related to said means and positioned each to be conductively engaged by one of said bar extensions of said frame 15 upon withdrawal of the latter from engage-

ment with said blade, and whereby said means are operatively energized and positioned to be conductively connected by engagement of said frame therewith upon withdrawal of the latter from engagement 20 with said blade and whereby said means are operatively energized.

Signed at Braintree, in the county of Norfolk and Commonwealth of Massachusetts, this 7th day of October, 1915.

MALCOLM H. BAKER.
